E. Q. Smith,

Making Chair Seats,

No 17,300,

Patented May 12, 1857

UNITED STATES PATENT OFFICE.

EDWARD Q. SMITH, OF CINCINNATI, OHIO.

MACHINE FOR PLANING CHAIR-SEATS.

Specification of Letters Patent No. 17,300, dated May 12, 1857.

To all whom it may concern:

Be it known that I, EDWARD Q. SMITH, of Cincinnati, in the county of Hamilton and State of Ohio, have invented certain new and useful Improvements in Machines for Cutting or Forming the Upper Surfaces or Face-Sides of Chair-Seats and Similar Articles; and I do hereby declare that the following is a full, clear, and exact description 5 of the same, reference being had to the accompanying drawings, making a part of this specification, in which—

Figure 1 is a longitudinal vertical section of my improvement; the plane of section 15 being indicated by the line (x) (x) in Fig. 3. Fig. 2 is a transverse vertical section of the same; the plane of section being indicated by the line (y) (y) in Fig. 3. Fig. 3 is a plan or top view of the same. Fig. 4 is 20 a detached side view of the roller which raises and lowers the cutter-shaft.

Similar letters of reference indicate corresponding parts in each of the several figures.

25 This invention relates to certain improvements in machines for cutting or forming the upper surfaces or face-sides of chair seats, and other articles having curved or irregular surfaces.

30 This invention consists in the combination, by means of a universally-jointed shaft, of a feed wheel, which derives its motion from the chair seat, with a cam which shifts the bearing of the cutter shaft.

35 To enable those skilled in the art to fully understand and construct my invention, I will proceed to describe it.

A represents a rectangular framing, which may be constructed of either wood or metal; 40 and B represents a driving shaft, which is placed transversely on the lower part of the framing.

At each side of the framing, A, on its upper part, two curved or segment guides, 45 C C, are attached. These guides may be constructed of cast iron, and the two at each side of the framing may be cast in one piece. The guides receive the bearings of two feed rollers, D D; the said bearings being fitted 50 loosely in the guides, and each having a pendent rod (b) attached; the said rods passing down through the top pieces of the framing, as clearly shown in Fig. 1.

Between the guides, C C, at one side of 55 the framing A, bearings, E, are secured; the said bearings having a small shaft, F,

fitted in them. The outer end of this shaft has a pulley, G, upon it, and a toothed wheel, H, is also placed on said shaft, adjoining the inner side of the pulley, G, as shown in 60 Figs. 2 and 3. The wheel, H, gears into the wheels, I, I, which are placed on the ends of the feed rollers, D, D, one on each.

J, represents a cutter-shaft, the bearings (c) (d) of which are fitted between the 65 lower ends of the guides, C. The bearing (c) is a permanent one, but the bearing (d) is allowed to slide up and down; its sides being fitted in grooves (e) in the sides or edges of the two guides between which it is 70 placed. The upper end of the bearing (d) has a yoke K attached to it; said yoke being also fitted in the grooves (e), see Fig. 3. A shaft (f) is fitted in bearings (g) (g) secured between the two guides above-mentioned. This shaft passes through the yoke, K; and the shaft (f) has an eccentric, (h), upon it; the eccentric being fitted and working within the yoke, as shown clearly in 75 Fig. 2. The inner end of the shaft (f) is 80 connected by a universal joint (i) with one end of a shaft, L, and the opposite end of this shaft has its bearing in a weighted lever, M, which is pivoted to one of the guides, C, as shown in Fig. 3. On the shaft 85 L, a feed wheel N is placed, the circumference of which is just equal, as regards measurement, to the width of the chair-seat or other article to be cut; the object of this will be explained hereafter.

90 The cutter-shaft, J, has one or more cutters (j) secured to it, the cutting edges of which are curved according to the character or form of the work to be produced; see Fig. 3, in which the cutter (j) is made of 95 the necessary or proper form to cut chair-seats. On one end of the cutter-shaft, J, a pulley, O, is placed.

P represents a table or bed, which rests upon bars, Q, Q, placed at the upper part 100 of the framing, A, one at each side. Both ends of these bars, at their under sides, are inclined, as shown at (k) (k) in Fig. 1; and these inclined surfaces or planes rest or are fitted in bearings (l) (l); the outer bearings (l) being attached to the inner sides of vertical plates, (m), at the front end of the framing; and the bearings (l') being attached to the lower parts of the inner sides of the bases of the guides, C. The outer 105 ends of the bars, Q, Q, have each a nut (n) attached to them, through which screws (o)

pass, one through each nut; the screws being fitted in bearings (*p*) at the sides of the bearings (*l*).

R represents a plate, which is attached to 5 the outer edge of the guides, C, at the end of the framing, by set screws, (*q*) (*q*), so that said plate may be adjusted to the desired height; and the plates (*m*) have slots (*r*) made through them, through which pass 10 screws (*s*); said screws passing into the edges of the table or bed P; see Fig. 3.

S represents a shaft, placed transversely on the framing, A, below the bed P. This shaft has a pulley (*t*) on its outer end, and 15 a belt (*u*) passes around this pulley and the pulley G on the shaft, F. A belt (*v*) passes around a pulley (*w*) on the driving shaft B, and around the pulley, O, on the cutter-shaft, J. The shaft, S, is driven by a belt 20 from the shaft, B.

The "stuff" to be operated upon (shown in red) is previously cut of the proper size, and is placed upon the bed P, face-side downward. The bed P is then adjusted to 25 the proper height to suit the thickness of the "stuff," by turning the screws (*o*) (*o*), which move the bars, Q Q; the said bars being either elevated or depressed, according to the direction in which they are moved, in 30 consequence of the inclined planes, (*k*) (*k*). The bed P will also be raised or lowered with the bars, as it rests upon them. The plate R is adjusted so as to be in the same plane as the bed P; sufficient space being 35 allowed between the ends of the plate and bed, to permit the cutter to work between them. The feed-rollers, D, D, bear upon the "stuff," and feed it over the cutter-shaft; said rollers being rotated in consequence of 40 the wheel H gearing into the wheels, I, I, on the rollers. The wheel N also bears upon the "stuff," which, as it is fed over the cutter, rotates said wheel and its shaft, L; the eccentric (*h*) is also rotated, and, by means 45 of the yoke K, raises and lowers the bearing (*d*) of the cutter-shaft, so that the face-side of the "stuff" will be cut in somewhat dish-form; for the eccentric is so formed as to gradually raise the end of the cutter-shaft, 50 as the cutter commences to act upon the "stuff"; the cutter-shaft being gradually elevated until the center of the "stuff" reaches the cutter; the end of the shaft then gradually descending. The wheel N and eccentric (*h*) make one revolution only, as 55 each piece of "stuff" passes underneath the wheel N; the eccentric being so placed at the commencement of the work that the shaft J may be at its lowest point. The bearing (*d*) of the cutter is thus shifted by means of the feed wheel N, which is not connected 60 with the driving power, but derives its motion from the chair seat itself, while the latter is passing through the machine.

65 If, from any cause, the seat sticks fast in

the machine, and refuses to move, the position of the cutter remains unaltered until the seat begins again to progress. This is a feature of great importance, because it prevents all damage to the seat in case of accident or of stoppage of the feed of the stuff. In other machines where the bearings of cutters are shifted, the shifting motion is generally imparted by means independent of the motion of the stuff, so that if the stuff ceases 75 to move while the other parts are left in motion, the cutter bearings continue to be shifted, and the stuff is spoiled.

In the use of other machines, much labor is required to sort out the various thicknesses 80 of seats before passing them through the machine; and a different adjustment is required for each change of thickness; for if the apparatus is set to cut thin seats, and thick stuff is then introduced, the cutters 85 must sink deeper into the thick seats than into the thin stuff, and thus a wrong formation of the concave is made, the work spoiled, etc., or the cutter bearing will not be shifted at the proper moment. No such 90 difficulty occurs in the use of my machine; if different thicknesses of stuff should be fed indiscriminately through the machine, the feed wheel N would accommodate itself to them, and would rise or fall according to 95 the thickness of the stuff, still continuing its regular rotation; the universal joint upon the shaft L allows the wheel N thus to adjust itself. Much time and labor at present lost in assorting the stuff, and adjusting, is 100 thus saved by my improvement.

It will be seen that the guides C are so curved as to form a part of a circle, concentric with the wheel H, so that the wheels, I, I, of the feed-rollers, will not be thrown 105 out of gear with the wheel H, in adjusting the bed, S.

The above machine has been practically tested, and operates rapidly and well. The pieces of "stuff" pass underneath the feed-rollers in contact with each other; and the work is produced in a uniform manner. 110

I do not claim, broadly, the shifting or lifting of cutter shafts or bearings thereof by means of cams, for this is an old and 115 well known method. Nor do I claim adjusting the table or carriage by means of wedges. But

What I claim as new, in chair-seat machines, is:

The combination, by means of the universally-jointed shaft L, of the feed wheel N with the eccentric (*h*), when the said wheel N derives its motion from the chair seat, substantially as and for the purposes 125 described.

EDWARD Q. SMITH.
